UNITED STATES PATENT OFFICE.

FRITZ W. MACHLET, OF ELIZABETH, NEW JERSEY.

PUMP, &c.

973,679.

Specification of Letters Patent.

Patented Oct. 25, 1910.

Application filed April 1, 1908. Serial No. 424,689.

To all whom it may concern:

Be it known that I, FRITZ W. MACHLET, a citizen of the United States, residing in Elizabeth, in the county of Union and State of New Jersey, have invented certain new and useful Improvements in Pumps, &c., of which the following is a specification.

This invention relates principally to liquid seals or packings for intergeared pistons of engines, air or gas pumps, blowers, etc., and more especially to blowers or air compressors.

While there is a great demand for low pressure air or gas pumps, still it has not heretofore been found practicable to secure by means of intergeared pistons a sufficient pressure to meet the demand. I have devised means whereby pumps or blowers of this class may be caused to deliver air or gas steadily at any required pressure up to twenty or more pounds per square inch, and may in some cases be used as air compressors.

The capacity of intergeared piston pumps has heretofore been limited by the leaking of air or gas past the edges and sides of the pistons, whenever it has been attempted to secure more than one or two pounds pressure to the square inch. I have devised means for effecting a constant circulation of liquid or lubricant through the pump in such a manner as to seal the edges and ends of the pistons sufficiently to enable pressure of the delivered air or gas to be raised far above that which has heretofore been found practicable, and have thus converted a low pressure blower to a moderate pressure or even high pressure air or gas compressor.

In the preferred form of practicing the present invention, each of the intergeared pistons is made in the form of a shell, and the liquid or lubricant is forced into the chambers of each piston under sufficient pressure to cause the liquid to ooze or exude from the pistons between the side edges thereof and the side walls of the drum in which they revolve, whereby said side edges are sealed, and leakage of air or gas is prevented. I provide also a basin beneath the pistons to catch the drip therefrom, and the accumulated drip is taken up by the inflowing air and delivered to the revolving pistons, to be swept around by the vanes or lobes thereof, thus forming seals between the ends of the pistons and the inner peripheries of the drum, and also forming seals between

the intermeshing lobes of the pistons. Preferably the lobes are relatively numerous to increase the number of seals, so as to make many barriers for the compressed air between the delivery and intake sides of the pump, whereby liability of leakage is minimized or avoided.

The intermeshing vanes or lobes of the pistons may run in contact with one another, thus tending to restrict the escape of compressed air past the same; and the presence of the liquid seal between the meshing lobes makes such escape practically impossible. When the intermeshing pistons are also provided with controlling gears, there may be slight clearances between the meshing lobes of the pistons, and said clearances may be readily sealed by the liquid swept around by the pistons.

Upon the delivery side of the engine, pump, or compressor, I preferably arrange a separator to collect the liquid, which is thence led back through ports in the side wall or walls of the drum, and introduced again into the chambers of the pistons. It will be understood that the pressure of the delivered air or gas is sufficient to force the liquid back to said pistons, so that the circulation of the liquid into and out of the pump is practically unintermittent, and hence the sealing is constant. The liquid is also forced by the same means through other joints in the pump to seal the same, with great resultant economy of operation.

In the accompanying drawings, Figure 1 is a transverse sectional elevation of one form of blower or compressor embodying my improvements; the pistons being shown full of the sealing liquid. Fig. 2 is a longitudinal section of the same. Fig. 3 is an enlarged diagrammatic cross section of the intermeshing lobes of the pistons illustrating the clearance therebetween. Fig. 4 is a sectional plan of the blower.

Within a drum 1, comprising two opposed C-shaped segments 2, 3, revolve pistons 4, 5, each having for instance six lobes or vanes 6 to intergear with the lobes of the other piston. Each piston is chambered and preferably made in the form of a shell, whose convolutions are united by a web 7 to a hub 8. By means of said hubs, the pistons are secured upon shafts 9, 10, respectively, the shaft 10 carrying a fly-wheel or pulley 11.

The liquid for sealing and lubricating the pistons is seen at 12 within a separator 13 of

any suitable type, and conveniently erected upon the top or delivery side of the pump directly over the delivery orifice 14 thereof. The liquid is caused by the pressure of the 5 delivered air or gas to flow down through a pipe or siphon 15, having at its lower end branches 16, 17, to enter ports 18, 19 in the side walls 20 of the drum; said ports being arched so as always to be within the contour 10 of the pistons and deliver the liquid directly into the chambers thereof. The pressure upon the liquid in the separator 13 is sufficient to force it to exude from the side edges of the pistons, to form films or seals between 15 said edges and the side walls 20, 21 of the drum, to prevent leakage of compressed air or gas past the same. It will be seen, Figs. 2 and 4, that the end of each hub is cut off to form an open passage 22 on the end thereof 20 of adjacent to the ports 18, 19, so as to increase the facility of communication between each port and all of the chambers in its associated piston.

The drip from the pistons and walls is 25 caught in a basin 23 formed in the blower below the intake orifice 24 thereof, so that the accumulated drip seen at 25 may be taken up by air or gas entering through the inlet pipe 26, and delivered to the lobes or 30 vanes of the pistons as indicated at 27, to be swept around thereby as indicated at 28, the films of liquid forming between the tips or ends of the vanes and the inner periphery of the segments 2, 3 of the drum. These 35 films are sufficient to prevent leakage of air or gas. Each film affords a substantial obstacle to leakage; and when the lobes of each piston are numerous, as illustrated, so that there are always three or four films around 40 the drum between the delivery and intake sides thereof, loss of air pressure through leakage is practically avoided; and the same holds true as to the sides of the pistons, there being always many films at the side edges 45 to coöperate to prevent loss of compressed air.

At Fig. 1, the particles of liquid are indicated at 29 in the column of ascending air; and it will be understood that said particles 50 may sometimes settle between the intermeshing lobes as at 30, to join the liquid 28 swept around by the tips of the pistons, which forms seals between the intermeshing convolutions of the pistons, so that leaking of 55 air through such intermeshing portions is minimized or avoided.

It will thus be seen that a constant circulation of the liquid is maintained from the separator 13 through the pump and back to 60 the separator.

Upon the piston shafts 9, 10 outside of the drum may be secured meshing gears 31, 32; although not in all cases necessary. When the gears are employed, there may be left a 65 slight clearance as at 33, Fig. 3, between the

intermeshing lobes of the pistons, to avoid friction; this clearance being however filled by the portion 30 of liquid to form a seal and prevent leakage. The gears 31, 32 should be sealed, as by inclosing them in a 70 box 34 formed on the outside of the drum wall, and provided with a cover 35 having a tight joint with the edges of the box to prevent possible escape of air which may work out between the shafts and, their bearings 75 36, 37. The opposite end of the shaft 9 may be sealed by a cap 38 tightly secured upon the boss 39 in which this end of the shaft turns, to prevent leakage of air.

In the boss 40 carrying the main shaft 10 80 is formed a recess 41 around the shaft, and a pipe 42 conducts liquid which works out along the shaft, down to the catch-basin 23. A ring 43 may be placed around the shaft within the recess 41. It will be understood 85 that the film of liquid, which may surround that portion of the shaft contained in the boss 40, serves as a seal to prevent leakage of air.

Variations may be resorted to within the 90 scope of the invention, and portions of the improvements may be used without others.

Having thus described my invention, I claim:

1. A rotary engine, gas or air pump or 95 blower comprising a drum, intergeared hollowed open-ended pistons revolving within the drum and fitting to the interior walls thereof, and means for forcing liquid or lubricant into the pistons under pressure, to 100 cause it to exude between the side edges of the pistons and the side walls of the drum to form seals or packings for said edges.

2. A rotary engine, gas or air pump or 105 blower comprising a drum, intergeared hollowed open-ended pistons revolving within the drum and fitting to the interior walls thereof, and means for forcing liquid or lubricant into the pistons under pressure, to cause it to exude between the side edges of 110 the pistons and the side walls of the drum to form seals or packings for said edges, and for collecting the exuded liquid and causing it to be forced again into the pistons to maintain a circulation of the liquid through 115 the pistons.

3. A rotary engine, gas or air pump or 120 blower comprising a drum, intergeared hollowed pistons having openings in their sides and revolving within the drum and fitting to the interior walls thereof, and means to force liquid into the pistons and causing the liquid to exude from said openings in the side edges thereof; said forcing means including a source of supply for the liquid, and ports communicating with said source and formed in the side walls of the drum opposite the hollows of the piston.

4. A rotary engine, gas or air pump or 125 blower comprising a drum, intergeared hol-

5 lowered pistons having openings in their sides and revolving within the drum and fitting to the interior walls thereof, and means to force liquid into the pistons and causing the liquid to exude from said openings in the side edges thereof; said forcing means including a source of supply for the liquid, and ports communicating with said source and formed in the side walls of the drum opposite the hollows of the pistons; said ports having such form and position as to be constantly within the contours of the pistons.

10 5. A rotary gas or air pump or blower comprising a drum, intergeared hollowed pistons having openings in their sides and revolving within the drum and fitting to the interior walls thereof, a separator to collect liquid from the delivery side of the pump, and means to enable the pressure of the delivered air or gas to force the collected liquid into said pistons to cause it to exude from said openings in the side edges thereof; a catch-basin for the drip from the pistons being provided upon the intake side of the pump to enable the inflowing air or gas to take up the liquid caught in the basin and deliver it to the vanes of the pistons to be thereby carried around to the delivery side of the pump.

20 30 6. A rotary gas or air pump or blower comprising a drum, intergeared hollowed open-ended pistons revolving within the drum and fitting to the interior walls thereof, and means dependent upon the operation of the pump or blower to force liquid to circulate through said pistons.

40 45 7. A rotary gas or air pump or blower comprising a drum, intergeared hollowed pistons having openings and revolving within the drum and fitting to the interior walls thereof, and means dependent upon the operation of the pump or blower to force liquid to circulate through said pistons and exude from said openings; said circulating means including a separator to collect liquid from the delivery side of the pump, and a basin to catch the drip from the pistons on the intake side of the pump.

50 55 8. A rotary gas or air pump or blower comprising a drum, intergeared hollowed pistons having openings and revolving within the drum and fitting to the interior walls thereof, a separator to collect liquid from air or gas delivered by the pump, and means for conducting the collected liquid into the pistons and causing it to exude therefrom through said openings to form packings or seals.

60 65 9. A rotary gas or air pump or blower comprising a drum, intergeared hollowed pistons having openings and revolving within the drum and fitting to the interior walls thereof, a separator to collect liquid from air or gas delivered by the pump, and ports communicating with said separator and

formed in the drum opposite the hollows of the pistons; means being provided to cause the liquid to flow from said separator through the pistons and exude from the openings therein.

70 10. A rotary gas or air pump or blower comprising a drum, intergeared hollowed pistons having openings and revolving within the drum and fitting to the interior walls thereof, a separator to collect liquid from air or gas delivered by the pump, means being provided to cause the liquid to flow from said separator through the pistons and exude from the openings therein, and means for collecting the liquid at the intake side of the pump, to be caught and swept around the drum by the ends of the piston teeth or vanes, to form packings or seals for the same.

80 85 11. A rotary gas or air pump or blower comprising a drum, intergeared hollowed pistons having openings and revolving within the drum and fitting to the interior walls thereof, a separator to collect liquid from air or gas delivered by the pump, means being provided to cause the liquid to flow from said separator through the pistons and exude from the openings therein, and means for causing a certain portion of the exuded liquid to be collected and taken up and swept around by the ends of the teeth or vanes of the piston, to form packings therefor.

90 95 10. 12. A rotary engine, gas or air pump or blower comprising a drum, intergeared hollowed pistons having openings and revolving within the drum and fitting to the interior walls thereof, the hollows in each piston being in open communication with one another, and means for causing liquid to flow into the pistons and exude therefrom through said openings to seal or pack the pistons.

100 110 13. A rotary engine, gas or air pump or blower comprising a drum, pistons revolving within the drum, each piston in the form of a shell open at its ends and formed with radiating convolutions to intergear with the convolutions of the other piston, and means for causing liquid to circulate repeatedly through the pistons to form seals or packings for the edges or ends thereof.

115 120 14. A rotary engine, gas or air pump or blower comprising a drum, pistons revolving within the drum, each piston in the form of a shell open at its ends and formed with radiating convolutions to intergear with the convolutions of the other piston, ports in the walls of the drum in communication with ends of the pistons, and means for causing liquid to flow from the ports through the pistons to exude from their edges to seal the same; each of said pistons provided with a hub which is cut away or shortened at the port end of the piston, to

increase the facility of communication between the port and all the chambers of the piston.

15. A rotary engine, gas or air pump or blower, comprising a drum, pistons revolving within the drum, each piston in the form of a shell open at its ends and formed with radiating convolutions to intergear with the convolutions of the other piston, ports in the drum to communicate with the chambers of the pistons, and means dependent upon the pressure of the air, gas or steam flowing through the engine or pump, to cause liquid to circulate constantly through said ports and pistons and exude from the edges of the latter to seal or pack the same.

16. A rotary engine, gas or air pump or blower, comprising a drum, pistons intergeared to revolve within the drum, said pistons hollowed or chambered and having openings, and ports provided within the drum in communication through said openings with the chambers in the pistons, said drum having a delivery orifice on its top, a separator extending up from said orifice, and means to conduct the collected liquid to said ports.

17. A rotary engine, gas or air pump or blower, comprising a drum, intergeared chambered pistons revolving within the drum and having openings, ports within the drum to communicate through said openings with the chambers in the pistons, said drum having a delivery orifice in its top, a separator communicating with said orifice, and means to conduct the collected liquid to said ports; the drum being also provided in its bottom with an intake orifice and a basin to catch the drip from the pistons.

18. A rotary engine, gas or air pump or blower, comprising a drum, intergeared chambered pistons revolving within the drum and having openings, and means to force liquid through the pistons under pressure to exude from said openings and seal the pistons; said pistons being provided outside of said drum with a pair of suitable meshing gears within a sealed casing.

19. A rotary engine, gas or air pump or blower, comprising a drum, intergeared chambered pistons having openings and re-

volving within the drum, said pistons being provided with a pair of suitable meshing gears, and clearances being provided between the meshing convolutions of teeth of the pistons, and means to force liquid through the pistons and out of said openings under pressure, to cause the drip from the pistons to be taken up by the ends thereof and swept around the drum thereby to form seals in said clearances.

20. A rotary engine, gas or air pump or blower, comprising a drum, intergeared chambered pistons having openings and revolving within the drum and formed with clearances between the meshing portions or lobes of the pistons, the latter being provided with a pair of meshing gears, and means for causing liquid or lubricant to circulate through the blower, said circulating means comprising a basin from which the liquid is taken up by the inflowing air or gas and delivered to the ends of the pistons to be swept around thereby to form seals for said clearances, and also including a separator upon the delivery side of the blower, means being provided to cause the collected liquid to flow back through the pistons and to exude from said openings.

21. A rotary engine, air or gas pump or blower, comprising a pair of intergeared pistons confined within a drum and mounted upon a pair of shafts which are journaled in side walls of the drum, means for circulating liquid through the pump to seal the pistons, a pair of meshing gears secured upon said shafts outside of the drum and confined in a box formed upon a side of the drum, a cap tightly jointed to said box to prevent leakage of air, a leak-proof cap being provided at the other end of one of said shafts, a fly-wheel or pulley mounted upon the other end of the other of said shafts, and means for drawing off liquid that may work out from the pump along the fly-wheel shaft and conducting it to the intake side of the blower or engine.
